PNEUMATIC THREAD HOLDER

Richard G. Turner, Worcester, Mass., assignor to
 Crompton & Knowles Loom Works, Worcester,
 Mass., a corporation of Massachusetts

Application May 1, 1948, Serial No. 24,633

21 Claims. (Cl. 139—247)

1

This is a continuation in part of my copending application Serial No. 2726,298, filed February 4, 1947, and abandoned May 6, 1948.

This invention relates to weft replenishing looms and it is the general object of the invention to provide a simple pneumatic thread holder constructed to facilitate placement therein of the weft ends extending from reserve bobbins.

In weft replenishing looms the reserve bobbin magazine ordinarily has extending therefrom a large number of threads or weft ends which must be held taut for proper operation of the loom. In loading the magazine with reserve bobbins it is desirable to be able to introduce all the threads of a group into the mouth of the holder at one time. In order to accomplish this result it is an important object of my present invention to provide the thread compartment of the holder with a cover or the like which can be temporarily displaced from its normal position to permit the weft ends to be moved into the intake mouth, after which the cover returns to its normal position to close the thread compartment.

It is another object of the present invention to provide a thread compartment having opposite walls in each of which is located a thread notch the top boundary of which is formed by the aforesaid cover. The weft ends extend across the thread compartment under the cover and through both of the thread notches and when the cover returns to its normal position subatmospheric pressures within the thread compartment draw the threads thereinto under the cover.

It is a further object of the invention to provide a stop or the like to limit movement of the cover and also serve as limiting means for the weft ends to prevent the latter from moving beyond the notches when being introduced into the holder.

It is desirable to be able to place weft ends of bobbins freshly inserted in the magazine into the thread holder by a single operation which can be performed with one hand, and with this thought in mind it is a further object of the invention to provide the cover with a lifting part under which the fresh weft ends can be passed and then raised to lift the cover. The part of the cover which is raised by the weft ends should be so located that threads in lifting relation with it will not be interfered with by any part of the thread collector. With these and other objects in view which will appear as the description proceeds, my invention resides in the combination and arrangement of parts hereinafter described and set forth.

In the accompanying drawings, wherein two

2

convenient embodiments of my invention are set forth,

Fig. 1 is a side elevation of part of a weft replenishing loom having the preferred form of the present invention applied thereto,

Fig. 2 is an enlarged plan view of the thread holder looking in the direction of arrow 2, Fig. 1.

Fig. 3 is a vertical section on line 3—3, Fig. 2, showing the thread holder and part of the thread collector depending therefrom,

Figs. 4 and 5 are side elevations of the thread holder looking in the direction of arrow 4 and 5, respectively, Fig. 3.

Fig. 6 is a diagrammatic elevation similar to Fig. 2 showing the relationship between the various groups of fresh weft ends and the cover preparatory to lifting the latter,

Fig. 7 is a view similar to Fig. 2 but shows a modified form of the invention, and

Fig. 8 is a side elevation of the structure shown in Fig. 7 looking in the direction of arrow 8, Fig. 7.

Referring particularly to Fig. 1, the loom frame 10 supports an air pump 11 having a piston 12 operated by a rod 13 connected to the upper end of an actuator lever 14. The latter is pivoted as at 15 to some convenient part of the loom and is operated by rod 16 connected to the lay L. The lay is reciprocated in usual manner by the top or crank shaft 17 and the usual connectors one of which is shown at 18. A hose or tube 19 extends forwardly from the pump 11 and communicates pneumatically with the interior of a thread collector C through the bottom thereof.

The loom frame supports a magazine M preferably of the multicolor type and having stored therein a complement of reserve bobbins B from which weft ends W extend laterally from the magazine in a direction away from the loom to the holder H forming the subject matter of this invention.

Except for the holder H to be described herein-after the matter thus far described has heretofore been proposed by me and operates in known manner. During backward movement of the lay the piston 12 creates subatmospheric pressures within the hose 19 and thread collector C for the purpose of drawing the weft ends W taut. Whenever there is a weft replenishing operation of the loom one or another of the bobbins B will drop from its stack to a common transfer position at the bottom of the magazine and will then be inserted into the shuttle S by the transerrer arm 20. The shuttle S is then picked to the opposite side of the loom with the fresh bobbin therein and the weft end leading from the shuttle will be held by the

holder H to effect at least partial threading of the shuttle. On a subsequent beat of the loom this thread will be cut at the salvage by means not shown herein but well understood and then be pneumatically drawn into the holder H and collector C.

In carrying the present invention into effect the holder H is provided with a base 30 which fits the upper part of the cylindrical collector C and has extending therethrough a thread opening or port 31 leading to the interior of the thread collector. Extending upwardly from the base is a substantially rectangular structure 32 having front and back walls 33 and 34 and side walls 35 and 36. The wall 35 is provided with a recess or thread notch 40 extending along part of the top thereof and of substantial width as will be apparent from Fig. 2, while wall 36 has a second thread notch 41 of less width in the top thereof. The tops of the walls 33-36, except for the notches, lie substantially in a plane which may be inclined downwardly and away from the magazine.

In order to close the top of the rectangular structure 32 I provide a thin preferably transparent flat cover 45 which may be attached as by a hinge 46 to the rear wall 34. The hinge permits the cover to lie flat against the tops of the walls and also permits the cover to be raised. The front edge of the cover projects forwardly from the front wall 33, as at 41, to facilitate raising of the cover. The aforesaid walls 33-36, the plate 30, and the cover 45 inclose a thread compartment 50 which communicates with the interior of the thread collector C by means of the port 31, but is otherwise closed to the atmosphere except for notches 40 and 41.

A wire guard 52 extends over the rear part of cover 45 as indicated in Fig. 2 and has vertical arms 53 and 54 secured to the base 30 close to the rear ends of the recesses 41 and 40, respectively, to serve as limits to determine the rear-most position which the weft ends W can occupy. The guard prevents the cover 45 from swinging upwardly too far to permit return thereof by gravity. The cover and recess 40 form an intake mouth 60 for holder H, while recess 41 and the cover form a thread orifice 61.

In operation, the cover 45 will normally be in the down closed position indicated in Figs. 3 and 5 and in full lines in Fig. 4. The weft ends will extend through the intake mouth 60 and downwardly through the port 31 into the interior of the collector C. Because of subatmospheric pressures existing within the thread collector the weft ends W will be held taut. As successive replenishing operations occur the weft ends will be cut one after another at the selvage and be drawn through the mouth 60 and port 31 into the collector C.

When it is necessary to add new bobbins to the magazine several inches of their weft ends will be drawn off and they will then be placed in the magazine, after which the weft ends will be passed under the overhang 47 of cover 45 and then raised to lift the latter, as shown in dotted lines, Fig. 4. The weft ends are then moved rearwardly under the cover and into recesses 40 and 41. The cover thereupon returns to normal position and the threads extend through compartment 50 and beyond the orifice 41. The partial vacuum within thread compartment 50 draws the outer ends of the threads inwardly through orifice 41 into the thread compartment and then down through the port 31 into collector C. Those

parts of the weft ends attached to the bobbins pass through mouth 60 and are drawn one by one through the mouth into compartment 50 as replenishing operations occur.

Inasmuch as the upper part of the thread compartment 50 is closed except at the intake mouth and orifice there is no opportunity for the thread ends hanging from the orifice to enter under the cover, since the latter is held tightly against the upper parts of the walls inclosing the thread compartment 50 whenever there is sufficient reduced pressure within the compartment to draw threads thereinto.

Another feature of the invention relates to the manner in which the cover can be raised by means of upward movement of weft ends leading from bobbins freshly inserted into the magazine. In the preferred form of the invention indicated diagrammatically in Fig. 6 the cover 45 is provided with lifting extension 65 formed with a hook 66 extending forwardly or to the left as viewed in Fig. 6 from the cover 45 and defining a notch 67.

The holder H is held to the thread container 25 C by means of rods 68 and 69 tapped at their upper ends into base 30. The hook 66 should be so located that neither the rod 68 nor the cylinder C can prevent entry of the fresh weft ends into notch 67.

As shown in Fig. 6, the four groups of weft ends may be considered as originating from the points I-IV corresponding to the four stacks of bobbins shown in the magazine in Fig. 1. Weft ends leading from position I, corresponding to the bobbins of the front stack, will be passed under the extension 65 and beyond the rod 68 as indicated by line a and be in position to enter the notch 67 due to the fact that the threads are inclined downwardly from the bobbins in the magazine toward cover 45. The threads following line a can then be lifted to raise the cover and moved rearwardly, as already described. Should the threads be accidentally moved forwardly the hook will prevent them from slipping out from under the cover. Weft ends from the other positions II, III and IV will follow generally the direction of lines b, c and d all of which, as will be apparent from Fig. 6, will clear the rod 68.

The extension 65 permits the weaver to hold 50 the bobbins being inserted in the magazine with the left hand for instance and with the right hand move their weft ends first under the hook 65, then upwardly to raise the cover, and then rearwardly to locate the weft ends in the thread compartment.

The modified form of cover 70 shown in Figs. 7 and 8 performs the same general function as does the cover 45, and has an extension 71 the forward end of which is bent down to form a hook 72. The relation between this hook and the cylinder C is substantially as described in connection with Fig. 6.

The intake mouth in the preferred form of the invention is formed by an upwardly opening recess in the wall 35, see Fig. 3, but in the modified form of the invention wall 35 is replaced by a wall 73 which is straight across its top and not provided with a recess, see Figs. 7 and 8. The cover 70 is formed with a recess or notch 74 which as viewed in Fig. 7 extends outwardly beyond the wall 73 with respect to the magazine to define an intake mouth 75 for reception of the weft ends W. The cover 70 is provided with a downwardly extending guide or stop 76 formed at the 70 front of recess 74 to engage the weft ends and

prevent them from passing under and being caught or pinched between the cover 70 and the wall 73 when the cover returns to its normal closed position.

When weft ends are placed under the cover preparatory to movement into the thread compartment in either the preferred or the modified form of the invention, they are likely to extend downwardly from the magazine toward the cover and then upwardly away from the cover or to the right as viewed for instance in Fig. 3 as the threads are raised to lift the cover. In order to facilitate rearward movement of the upwardly extending threads beyond the hooks 66 or 72 the covers are provided with inclined edges which extend from the hooks rearwardly and outwardly with reference to the magazine. Thus, cover 45 as shown in Fig. 6 has an inclined edge 77 while cover 70 has a similar edge 78.

From the foregoing it will be seen that I have provided a simple form of pneumatic thread holder having a thread compartment the upper part of which is closed by a cover which can be lifted temporarily to permit movement of threads thereunder into the recesses 48, 41 or 74. After being lifted to admit threads the cover drops to form the upper parts of mouth 60 and orifice 61. While the cover has been shown as hinged for upward movement, I do not wish to be thus limited in the practice of my invention. The vertical stops or arms 53 and 54 limit backward movement of the weft ends to prevent them from becoming pinched between the cover and the tops of the side walls 35 and 36, but I do not wish to be limited to the particular stops set forth herein. It will also be noted that the covers are provided with lifting extensions under which the weft ends of bobbins freshly inserted into the magazine may be passed preparatory to upward movement to raise the cover. These extensions or hooks on the covers are located at a position far enough forward of other parts of the thread holder and collector so that the latter will not interfere with the threads as they are raised. It should be understood that the hooks 66 and 72 will not be necessary in all instances. Also, it will be seen that the parts 35 or 73 can be considered wall members and the parts 45 and 70 cover members which cooperate when the cover member is in normal position to form thread intake mouths, and orifice 41 and the intake mouths 60 and 75 may be considered as inlets connecting the atmosphere with the thread compartment.

Having thus described my invention it will be seen that changes and modifications may be made therein by those skilled in the art without departing from the spirit and scope of the invention and I do not wish to be limited to the details herein disclosed, but what I claim is:

1. In a pneumatic thread holder for the weft ends of reserve bobbins in a loom, a hollow structure formed of walls surrounding a thread compartment in which subatmospheric pressures exist, one of said walls having a recess therein communicating with the atmosphere and compartment, a cover extending across said thread compartment and recess and forming with the latter an intake mouth for said weft ends, and means mounting the cover for movement away from said recess to enable said weft ends to pass between certain of said walls and cover into said recess.

2. In a pneumatic thread holder for the weft ends of reserve bobbins in a loom, means defining a base, while upstanding from said base surround-

ing a thread compartment in which subatmospheric pressures can be created, the top of one of said walls having a recess therein opening upwardly and communicating with the atmosphere and the compartment, a cover extending across said thread compartment and recess and forming with the latter an intake mouth for said weft ends, and means mounting said cover for movement in a direction away from said recess to afford entry of said weft ends into said recess.

3. In a pneumatic thread holder for the weft ends of reserve bobbins in a loom, a structure having a base and walls extending upwardly therefrom surrounding a thread compartment in which subatmospheric pressures can be created, a cover normally held across said thread compartment by the subatmospheric pressures within the compartment, one of said walls and said cover having cooperating parts defining an intake mouth for said weft ends, and means mounting said cover for movement in a direction away from said compartment to permit entry of the weft ends thereto.

4. In a pneumatic thread holder for the weft ends of reserve bobbins in a loom, means comprising a substantially horizontal base and vertical walls upstanding therefrom surrounding a thread compartment in which subatmospheric pressures can be created, and a cover normally held down in engagement with the tops of said walls by the subatmospheric pressures within the compartment and pivotally mounted on one of said walls for movement away from another of said walls, said other wall and said cover having cooperating parts forming an intake mouth for the weft ends, said cover being movable pivotally away from said other wall to permit entry of said weft ends into said intake mouth.

5. In a pneumatic thread holder for the weft ends of reserve bobbins in a loom, a structure including a base and walled means extending upwardly therefrom surrounding a thread compartment in which subatmospheric pressures can be created, the top of said walled means having formed therein on opposite sides thereof recesses communicating with the atmosphere and compartment, and a cover normally held against said wall means and extending across said recesses, said cover being constructed and mounted in such manner as to be movable away from said recesses to enable said weft ends to enter said recesses.

6. In a pneumatic thread holder for the weft ends of reserve bobbins in a loom, a structure comprising a base and walled means extending upwardly therefrom surrounding a thread compartment in which subatmospheric pressures can be created, said walled means having in the top thereof on one side thereof an upwardly opening recess communicating with the atmosphere and the compartment and having a similar recess on the side thereof opposite said one side, a cover normally held across said thread compartment by the subatmospheric pressures within the latter and extending over the first named recess to form an intake mouth and over the second named recess to define a thread orifice, and means mounting said cover for movement away from said recesses to permit entry of said weft ends into said recesses and across the thread compartment.

7. In a pneumatic thread holder for the weft ends of reserve bobbins in a loom, a hollow structure surrounding a thread compartment in which subatmospheric pressures can be created, a cover fitting over said structure and cooperating with

the latter to inclose said compartment, said cover and the upper parts of said structure having cooperating parts defining spaced air inlets communicating with the atmosphere and the compartment, and means mounting the cover for movement away from said hollow structure to permit entry of said weft ends into said inlets.

8. In a pneumatic thread holder for the weft ends of reserve bobbins in a loom, a hollow structure having substantially vertical walls inclosing a thread compartment in which subatmospheric pressures can be created, spaced upwardly opening recesses in the tops of certain of said walls communicating with the atmosphere and compartment, a cover closely fitting the top of said hollow structure extending over said recesses, and means mounting said cover for movement relatively to the hollow structure in a direction to expose said recesses for insertion therein of said weft ends.

9. In a pneumatic thread holder for the weft ends of reserve bobbins in a loom, means comprising a base and front and back and side walls extending upwardly therefrom surrounding a thread compartment in which subatmospheric pressures can be created, and a cover pivoted on the back wall and extending across the other walls and held in normal position against said other walls due to the subatmospheric pressures within the compartment, each of the side walls having an upwardly opening recess therein under the cover communicating with the atmosphere and compartment, said cover when moved upwardly exposing said recesses for entry thereinto of said weft ends.

10. In a pneumatic thread holder for the weft ends of reserve bobbins in a loom, a hollow structure formed of walls surrounding a thread compartment in which subatmospheric pressures can be created, one of said walls having a recess therein communicating with the atmosphere and compartment, a cover extending across said hollow structure and recess and forming with the latter an intake mouth for said weft ends and having a part projecting beyond one of said walls, and means mounting the cover for movement away from said recess by a force exerted against said part of the cover by the weft ends to enable the latter to pass between said one wall and cover into said recess.

11. In a pneumatic thread holder for the weft ends of reserve bobbins in a loom, means comprising a base and front and back and side walls extending upwardly therefrom surrounding a thread compartment in which subatmospheric pressures can be created, a cover pivoted on the back wall and extending across the other walls and held in normal position against the latter due to the subatmospheric pressures within the compartment, said covered one of said side walls having cooperating parts defining a thread intake mouth for the weft ends, and a thread stop adjacent to the rear end of said intake mouth, said cover being movable upwardly away from said one side wall to afford entry into the intake mouth by said weft ends and said stop preventing movement of said weft ends beyond the rear end of said mouth.

12. In a pneumatic thread holder for the weft ends of reserve bobbins in a loom, means comprising a base and front and back and side walls extending upwardly therefrom surrounding a thread compartment in which subatmospheric pressures can be created, a cover pivoted on the back wall and extending over the front and side

walls, said cover and side walls having cooperating parts defining an air inlet for each side wall through which the compartment communicates with the atmosphere, and a thread stop located near the rear end of each inlet, said cover being movable upwardly to afford entry of said weft ends into said inlets and said stops preventing said weft ends from moving beyond the rear ends of said inlets.

13. In a thread holder for the weft ends of reserve bobbins in a loom, said holder comprising a walled structure surrounding a thread compartment in which subatmospheric pressures can be created, the upper part of said walled structure having therein an upwardly opening recess communicating with the atmosphere and compartment, and a cover extending across said walled structure and over the recess and forming with the latter an intake mouth for the weft ends, said cover having a part projecting beyond said walled structure for engagement with the weft ends to enable the latter by a force exerted thereby to move the cover away from the recess to afford entry into the latter of said weft ends.

14. In a pneumatic thread holder for the weft ends of reserve bobbins in a loom, a hollow structure formed of walls surrounding a thread compartment in which subatmospheric pressures exist, one of said walls having a recess therein communicating with the atmosphere and compartment, and a cover extending across said walled structure and recess and forming with the latter an intake mouth for said weft ends, said cover being constructed and mounted in such manner as to be movable away from said recess to enable said weft ends to enter said recess.

15. In a pneumatic thread holder for the weft ends extending from reserve bobbins in a weft replenishing loom, a hollow structure including a wall member and formed with a hollow thread compartment in which subatmospheric pressures can be created, a cover member mounted on the structure for movement relatively to the wall member and when in normal position closing the top of said structure, and cooperating parts on said wall and cover members forming a weft end intake mouth connecting the thread compartment to the atmosphere, said cover member being movable away from said wall member to enable said weft ends to enter the intake mouth.

16. In a pneumatic thread holder for the weft ends of reserve bobbins in a loom, a hollow structure forming a thread compartment in which subatmospheric pressures may be created, a cover extending across said compartment, said structure and cover having cooperating parts which define an intake mouth for the weft ends communicating with the compartment and atmosphere, and means mounting said cover for movement away from said compartment to enable the weft ends to enter said intake mouth.

17. In a pneumatic thread holder for the weft ends of reserve bobbins in a loom, a hollow structure surrounding a thread compartment in which subatmospheric pressures may be created, a cover for the structure normally in position to close the compartment but movable upwardly from said compartment to open the latter, said structure and cover having parts cooperating to define an intake mouth for the weft ends when the cover is in normal position, and an extension on the cover projecting beyond said structure against which the weft ends may be raised to lift the cover to permit entry of the weft ends into said intake mouth.

18. In a pneumatic thread holder for the weft ends of reserve bobbins in a loom, a hollow structure formed of walls surrounding a thread compartment in which subatmospheric pressures may be created, a cover normally in position to close the upper part of the compartment, one of said walls and said cover when in normal position defining an intake mouth for the weft ends and connecting the interior of said compartment with the atmosphere, means mounting said cover on said structure enabling the cover to be lifted relatively to said walls to permit entry of the weft ends into said intake mouth, and an extension on said cover projecting beyond said walls against which the weft ends may be raised to lift the cover.

19. In a pneumatic thread holder for the weft ends of reserve bobbins in a loom, a hollow structure surrounding a thread compartment in which subatmospheric pressures may be created, a cover for the structure normally in position to close the compartment but movable upwardly from said compartment to open the latter, said structure and cover having parts cooperating to define an intake mouth for the weft ends when the cover is in normal position, an extension on said cover projecting beyond said structure against which the weft ends may be raised to lift the cover and open the compartment for entry of the weft ends into said intake mouth, and a hook on said ex-

30

tension limiting movement of weft ends engaged therewith in a direction away from said structure.

20. In a pneumatic thread holder for the weft ends of reserve bobbins in a loom, a hollow structure surrounding a thread compartment in which subatmospheric pressures may be created, a cover for the structure normally in position to close the compartment but movable upwardly from said compartment to open the latter, an extension on said cover projecting beyond said structure against which the weft ends may be raised to lift the cover and open the compartment for entry of the weft ends thereinto.

21. In a pneumatic thread holder for the weft ends of reserve bobbins in the magazine of a weft replenishing loom, a hollow structure surrounding a thread compartment in which subatmospheric pressures can be created, a cover for said structure movable upwardly relatively to the latter away from said compartment, an extension on said cover forward of said structure under which the weft ends may be passed and then raised against the extension to lift the cover, said cover having a thread engaging edge extending rearwardly from said extension in a direction away from the magazine.
